UNITED STATES PATENT OFFICE.

BENJAMIN B. KEEPORT AND DAVID H. KEEPORT, OF PERU, INDIANA.

COMBINED RIDING AND DRIVING WHIP AND CANE.

No. 918,557.

Specification of Letters Patent.

Patented April 20, 1909.

Application filed August 30, 1906. Serial No. 382,707.

To all whom it may concern:

Be it known that we, BENJAMIN B. KEEPORT and DAVID H. KEEPORT, citizens of the United States, residing at Peru, in the county of Miami and State of Indiana, have invented certain new and useful Improvements in a Combined Riding and Driving Whip and Cane; and we do hereby declare the following to be a full, clear, and exact 10 description of the invention, such as will enable others skilled in the art to which it appertains to make and use the same, reference being had to the accompanying drawings, and to the letters of reference marked 15 thereon, which form a part of this specification.

This invention relates to new and useful improvements in combined canes and whips, and the object of the invention is to produce 20 a simple and efficient device of this nature comprising a convertible article which may be used either as a cane or whip, and comprises various details of construction and combinations and arrangements of parts 25 which will be hereinafter fully described and then specifically defined in the appended claim.

We illustrate our invention in the accompanying drawings, in which:—

30 Figure 1 is a perspective view showing our device adjusted for use as a cane. Fig. 2 is a view showing the cane converted into a whip, and Fig. 3 is a detail perspective view of the cane portion, showing the structural arrangement of the parts. Fig. 4 is a longitudinal sectional view through the parts, one inclosed within the other.

Reference now being had to the details of the drawings by letter, A designates a shell 40 which is adapted to have a cap B telescoping over the same to hold the whip C within the hollow cane portion, when the device is adjusted for use as a cane.

D designates a ferrule which is fastened 45 to one end of the cane part, and E, E designate steel strips which connect said shell and ferrule and which are also connected to the circumference of a band or ring G midway between said shell and ferrule, thereby holding said strips spaced apart and rigid.

A suitable covering N is placed about said 50 ribs in order to form a closure about the same and protect and conceal the whip contained therein, when the device is adjusted for use as a cane. Said whip has a ferrule O at one end which is adapted to 55 telescope over the ferrule at the end of the cane section, when it is desired to adjust the device for use as a whip. In order to secure the two ferrules in their telescoping relation when the device is used for a whip, 60 we provide a spring fastener R which is carried by the ferrule upon the cane section and adapted to engage and securely hold the whip section, thereby preventing the 65 same from separating from the butt or cane section.

From the foregoing, it will be noted that by the provision of the device shown and described, a simple and efficient means is afforded which may be utilized either as a 70 cane or as a whip, the adjustment of the device for the former use being as shown in Fig. 1 of the drawings, and when open for use as a whip, as illustrated in Fig. 2.

What we claim is:—

In combination with a hollow tapering section, a ferrule at one end thereof, longitudinal ribs secured thereto, a shell fastened at the other ends of said ribs, a cylindrical ring intermediate said ferrule and shell and to the circumference of which said ribs are fastened longitudinally parallel to each other, said ferrule having an L-shaped recess formed therein, a resilient hook fixed at one end in said recess, a whip tip with a hollow section designed to telescope over the recessed portion of the ferrule and provided with an elongated slot adapted for the reception of the hook, as set forth. 80 85

In testimony whereof we hereunto affix 90 our signatures in the presence of two witnesses.

BENJAMIN B. KEEPORT.
DAVID H. KEEPORT.
